UNITED STATES PATENT OFFICE

90,561

DESIGN FOR A FLOOR LAMP BASE HOLDER

Louis L. Withey, Rome, N. Y.

Application June 8, 1933. Serial No. 48,351

Term of patent 14 years

To all whom it may concern:

Be it known that I, Louis L. WITHEY, a citizen of the United States, residing at Rome, in the county of Oneida and State of New York, have invented a new, original, and ornamental Design for a Floor Lamp Base Holder, of which the following is a specification, reference being had to the accompanying drawing, forming part thereof.

I claim:

The ornamental design for a floor lamp base holder as shown.

LOUIS L. WITHEY.
